CLAIM

The ornamental design for a battery powered ride-on electric vehicle, as shown and described.

DESCRIPTION

FIG. 1 is a top and front perspective view of a battery powered ride-on electric vehicle showing my new design;

FIG. 2 is a top plan view thereof;

FIG. 3 is a front elevation side view thereof;

FIG. 4 is a rear elevation side view thereof;

FIG. 5 is a left side elevation view thereof; and,

FIG. 6 is a right side elevation view thereof.

The broken lines showing the tires are provided for the purpose of illustrating environmental structure and forms no part of the claimed design.
